[57] **CLAIM**

The ornamental design for a ball point pen or similar
article, as shown and described.

DESCRIPTION

FIG. 1 is a front elevational view of a ball point pen or
similar article showing my new design;

FIG. 2 is an exploded right side elevational view
thereof;

FIG. 3 is a rear elevational view thereof;

FIG. 4 is a top plan view thereof;

FIG. 5 is a bottom plan view thereof; and

FIG. 6 is a perspective view thereof.
